UNITED STATES PATENT OFFICE.

HERBERT S. WOODWARD, OF CARBONDALE, PENNSYLVANIA.

MULTIPLE DECK SCREEN.

Application filed August 21, 1924, Serial No. 733,269.

My invention relates particularly to that class of screening or sifting devices wherein a plurality of foraminous diaphragms are maintained in spaced relation by separate frame units which may be conveniently secured together to form a composite screen structure in which said units are so integrally united as to be capable of severe vibration without accidental displacement.

The principal objects of my invention are to provide a screen structure of the type contemplated, in which the unit components may be readily separated to permit the free removal and replacement of the interposed foraminous diaphragms, and be quickly and conveniently clamped together to form an integral structure.

Other objects of my invention are to provide a multiple unit screen structure with means arranged to effect the separation of said units contemporaneously and to maintain them in substantially uniform spaced relation with respect to each other, irrespective of the amount of such separation.

My invention also comprehends novel means which serve not only to cause the units to register when approaching each other, but also to maintain them, as well as the foraminous diaphragm held therebetween, in alinement while being clamped.

Specifically stated, the form of my invention as hereinafter described, comprises a plurality of foraminous plates or reticulated diaphragms interposed between separate spacing units, which may preferably be hingedly connected to be oscillated about an axis spaced therefrom, and which may be connected with means arranged to effect their relative separation about said axis so as to radiate therefrom in fan-like relation and permit the convenient removal and replacement of said plates or diaphragms as desired.

My invention also includes all of the various novel features of construction and arrangement as hereinafter more definitely specified.

In the accompanying drawings, Figure 1 is a side elevational view of a screening apparatus of the multiple deck type, showing a convenient embodiment of my invention; Fig. 2 is an elevational view of the discharge end of the apparatus shown in Fig. 1; Fig. 3 is an elevational view of the intake end of said apparatus; Fig. 4 is a transverse vertical sectional view of said apparatus,

taken on the line 4-4 in Fig. 1; Fig. 5 is a central vertical longitudinal sectional view of the apparatus showing its units separated to permit the removal and replacement of the perforated diaphragms; Fig. 6 is a fragmentary detail sectional view, on an enlarged scale, showing the means for effecting alinement of the spacing frame units; and Fig. 7 is a fragmentary plan view showing a corner of one of the foraminous diaphragms.

The screening apparatus shown in said figures is provided with four decks comprising the foraminous diaphragms or perforated plates 1, 2, 3 and 4, the discharge pan 5 having the flanges 6, and comprising an imperforate channel of sheet material, and the cover deck, comprising the preferably imperforate plate 7.

The pan 5 and the perforated plate 4 are carried by the base frame comprising the side rails 8 which are connected at the initial or receiving end of the screen by the channel iron 9, formed U-shaped and having the free parallel arms thereof embracing the rails 8 and secured to the outside faces of said rails by the bolts 10.

Said base frame is mounted upon blocks or standards 12 through which it may preferably be bolted to the yielding frame bars 15 of the vibratory mechanism, which may be of any desired construction, the rails 8 and standards 12 upon opposite sides of the screen being conveniently connected by the transversely disposed angle irons 19 which not only connect the frame members but serve to stiffen the bottom of the pan 5.

The perforated plates 2, 3 and 4 and the cover plate 6 are maintained in relatively spaced relation by the spacing frame units comprising the side rails 22, 23, 24 and 26, respectively connected transversely by the channel irons 27, 28, 29 and 30 formed U-shaped and having their free parallel arms embracing their respective side rails 22, 23, 24 and 26 and secured to the outer faces thereof by the bolts 31, 32, 33 and 34.

Brackets 35 are secured to the channel iron 9 of the base frame and extend obliquely upward therefrom, affording bearings for the transversely extended shaft 36 which is prevented from axial displacement by the collars 37. The shaft 36 serves as an axis about which the spacing frame units may move or oscillate when separated, the channel irons 27, 28, 29 and 30 of said units being

respectively provided with the brackets 39, 40, 41 and 42 extended rearwardly and having bearings mounted on said shaft 36.

The cover deck or plate 7 is permanently secured to the side rails 22 of the upper spacing frame unit by the cap screws 43, and said plate 6 is provided with the inlet opening 44 embraced by the hopper 45 through which material to be screened is introduced.

10 In order to insure proper alignment of the frame units and their interposed diaphragms, the upper faces of the side rails 8, 23, 24 and 26 are provided with screws having heads 47 extended above said faces, 15 and arranged to project through suitable apertures 48 in the margins of the respective diaphragms 1, 2, 3 and 4 and extend into complementary sockets 49 in the under faces of the side rails 22, 23, 24 and 26 the heads 20 47 extended from the surface of the side rails 8 being also extended through apertures 50 in the flanges 6 of the pan 5.

The composite structure thus assembled may be rigidly held together by suitably 25 provided clamps which embrace said structure and which may preferably comprise the hasps 52 hingedly connected to the side rails 8 by the pintles 53 and having their free extremities 54 extended across the side 30 rails and terminating in the upwardly directed opposed ears 85, as best shown in Fig. 4. Said hasps are arranged to be connected by the through bolt or stay rod 86 which extends through said ears 85 and through the 35 spacing sleeve 87 serving as a gauge to properly space said hasps when the nuts 88 of said bolt 86 engage said ears.

The free extremities 54 of said hasps, 40 which extend transversely over the side rails, are preferably provided with set screws 90 which may be adjusted to impinge upon the cover plate 7, and thereby tend to bind or press the frame side rails against the opposite surfaces of the margins of the interposed plates or diaphragms.

Should it be desired to remove and replace any of the plates or diaphragms, the clamps 45 may be released and the hasps 52 thrown back upon their pintles 53, thus permitting the frame units to be separated and caused to assume a relatively inclined or fan-like position by oscillating them about the axis of the shaft 36, thereby allowing the plates or diaphragms which loosely rest upon said frame units to be withdrawn by merely lifting them sufficiently to clear the projecting heads 47 on the side rails of said units.

To facilitate the separation of the spacing units, their side rails 22, 23, 24 and 26, may 50 be provided near their free ends with inverted U-shaped bails 55, 56, 57 and 58 respectively, having the free ends of their parallel arms pivoted to the rails at 60, 61, 62 and 63, said bails being provided with the 55 eye-bolts 64, 65, 66 and 67 respectively con-

nected by flexible cables or chains 68, 69, 70 and 71, after passing over the drums 72 and 73, with the grooves 75, 76, 77 and 78 of the cone sheave 79, the grooves of which are of relatively different diameters, whereby rotation of the sheave is operative to effect the separation of said units at relatively different speeds.

The rotation of the cone sheave 79 may be effected by the crank handle 80 on the shaft 75 81 having the pinion 82 in toothed engagement with the gear 83 on the shaft 84 of the cone sheave.

It will be obvious that the unit 22 will be connected with the groove 75 of greatest 80 diameter, the unit 23 with the groove 76 of less diameter, the unit 24 with the groove 77 of still smaller diameter, and the unit 26 with the groove 78 of smallest diameter, so that when the cone sheave 79 is rotated the 85 relative rate of movement of said units will uniformly decrease from the top unit downward and their relative separation therefore be substantially uniform.

My invention is advantageous, in that the 90 cover and perforated plate supports are hingedly connected at the receiving end of the screen to oscillate about a common axis, and the entire assembly is clamped rigidly together in its operable form by the hinged clamps by which any desired degree of pressure may be exerted to hold the parts firmly together, while by the mere loosening of 95 said clamps and throwing them back out of the path of the screen units, said units may be raised by a fan-like movement about said axis and the entire assembly separated to permit the plates and pan to be readily removed and replaced without removing any other bolts or fastenings.

Although foraminous diaphragms and 100 perforated plates are herein referred to, it is to be understood that the screening medium may comprise a reticulated wire mesh or any other desired form of means for separating the relatively fine from the coarser particles.

I do not desire to limit my invention to the precise details of construction and arrangement as herein set forth, as it is obvious that various modifications may be made therein without departing from the essential features of my invention as defined in the appended claims.

Having thus described my invention, I 120 claim:

1. A screen comprising relatively spaced 125 perforated diaphragms, and a plurality of spacing units hingedly connected to be relatively moved about a common axis disposed away from said units, and between which units the margins of said diaphragms are extended and removably engaged when the screen is arranged for operative use.

2. A screen comprising relatively spaced 130

- perforated diaphragms, and a plurality of spacing units respectively having one end hingedly connected and arranged to be relatively moved about a common axis extended in spaced relation with respect to the hinged ends of said units, whereby adjacent units may be caused to engage or release the marginal edges of the diaphragm disposed therebetween.
- 10 3. A screen comprising relatively spaced perforated diaphragms, a plurality of spacing units hingedly connected to be relatively oscillated about a common axis disposed away from said units, and between which units the margins of said diaphragms may extend and be removably engaged, and clamping means embracing said units and arranged to lock said units and diaphragms together to form a rigid composite screen structure.
- 15 4. A screen comprising a plurality of relatively spaced perforated diaphragms, hingedly connected spacing units between which said diaphragms are arranged to be removably engaged, and means operative to relatively separate said units by simultaneously moving them about the axis of said hinged connection to permit removal of the diaphragms.
- 20 5. A screen comprising relatively spaced perforated diaphragms, a plurality of spacing units hingedly connected to be relatively moved toward and from each other about a common axis, and means arranged to relatively separate said units and to move them at such relatively different speeds that the spaces between adjacent units will be maintained substantially uniform.
- 25 6. A screen comprising relatively spaced perforated diaphragms, a plurality of spacing units between which the margins of said diaphragms may be removably engaged, means arranged to clamp said units and diaphragms together to form a rigid composite structure, and means arranged to simultaneously separate said units at one of their relatively adjacent ends while maintaining them in uniformly spaced relation irrespective of the extent of their relative separation.
- 30 7. A screen comprising relatively spaced perforated diaphragms, a plurality of frame units arranged to space said diaphragms apart and between which said diaphragms are removably engaged and rigidly held, means on said spacing units cooperatively registerable to insure alinement of said units and diaphragms, and means arranged to relatively separate said frame units simultaneously while preserving the same relative angular relation between adjacent units to permit the removal and replacement of said diaphragms.
- 35 8. A screen comprising relatively spaced perforated diaphragms, a plurality of frame units arranged to space said diaphragms apart, and between which the margins of said diaphragms are removably engaged and rigidly held, the opposed surfaces of said frame units respectively having recesses and projections complementary to each other, arranged to register and insure alinement of said units, and means including a drum having stepped pulleys of relatively different diameters respectively connected with said frame units and arranged, when actuated, to effect the separation of said units at relatively different speeds, whereby their substantially uniform separation may be simultaneously effected.
- 40 9. In a screen of the class described, the combination with a plurality of perforated diaphragms, of a plurality of frame units comprising lateral rails connected by U-shaped channel bars, and between which units the lateral margins of said diaphragms are arranged to be removably engaged and rigidly secured, a shaft extending parallel with the end of said frame units spaced therefrom exterior thereof and about which said units are arranged to be oscillated, a bail pivoted to each of said frame units, a rotatable drum connected with said bails, and arranged when rotated to effect the separation of said units about the axis of said shaft, and means arranged to actuate said drum.
- 45 10. In a screen of the class described, the combination with a plurality of perforated diaphragms, of a plurality of frame units arranged to maintain said diaphragms relatively spaced apart, and between which the margins of said diaphragms are arranged to be engaged, a base frame upon which said units are mounted for relative oscillation, locking means embracing the units and arranged to rigidly secure said frame units and diaphragms to said base frame and to readily release said parts, and means arranged to relatively rock said frame units on said base frame whereby said units may be contemporaneously separated and all of the diaphragms simultaneously released.
- 50 11. A multiple deck screen having a plurality of spacing frame units, a plurality of diaphragms rested upon the respective units and having their margins engaged therewith by the superjacent units, and means arranged to contemporaneously separate said units in fan-like relation, comprising a drum having cone pulleys respectively connected with said frame units.
- 55 In witness whereof, I have hereunto set my hand this eighteenth day of August, 1924.

HERBERT S. WOODWARD.
